UNITED STATES PATENT OFFICE

154,888

DESIGN FOR AN OIL BURNING SPACE HEATER

Irvin A. Sorenson, Albert Lea, Minn., assignor to
American Gas Machine Company, Albert Lea,
Minn., a corporation of Minnesota

Application March 26, 1948, Serial No. 145,390

Term of patent 14 years

(Cl. D81—19)

To all whom it may concern:

Be it known that I, Irvin A. Sorenson, a citizen of the United States and residing in the city of Albert Lea, Freeborn County, Minnesota, have invented a new, original, and ornamental Design for Oil Burning Space Heater, of which the following is a specification, reference being made to the accompanying drawing, forming a part thereof, wherein:

Fig. 1 is a view in front elevation of an oil burning space heater, showing my new design;

Fig. 2 is a view in side elevation of the same looking toward the right of Fig. 1;

Fig. 3 is a view in rear elevation of the oil burning space heater;

Fig. 4 is a plan view of the same; and

Fig. 5 is a vertical section taken in large scale through the upper grating of the heater substantially shown on the line 5—5 of Fig. 4 as is indicated by the arrows.

The opposite side of the space heater from that shown in Fig. 2 is substantially similar to the side shown.

I claim:

The ornamental design for an oil burning space heater, substantially as shown and described.

IRVIN A. SORENSEN.
